Primary Examiner — Mitchell I. Siegel

(57) CLAIM

The ornamental design for a golf club head, as shown and described.

DESCRIPTION

FIG. 1 is a top perspective view of a golf club head; FIG. 2 is a bottom perspective view of the golf club head of FIG. 1; FIG. 3 is a top view of the golf club head of FIG. 1; FIG. 4 is a bottom view of the golf club head of FIG. 1; FIG. 5 is a front view of the golf club head of FIG. 1; FIG. 6 is a rear view of the golf club head of FIG. 1; FIG. 7 is a heel side view of the golf club head of FIG. 1; FIG. 8 is a toe side view of the golf club head of FIG. 1; FIG. 9 is a top perspective view of a second embodiment of a golf club head.

FIG. 10 is a bottom perspective view of the golf club head of FIG. 9;

FIG. 16 is a toe side view of the golf club head of FIG. 9.

1 Claim, 10 Drawing Sheets
